CLAIM

The ornamental design for a blade for a mower, as shown and described.

DESCRIPTION

FIG. 1 is a front left perspective view of a blade for a mower showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a left side view thereof, the broken line showing of a plurality of blades for a mower shown in use condition form no part of the claimed design.

The broken lines depict environmental subject matter only and form no part of the claimed design.
